UNITED STATES PATENT OFFICE.

OWEN R. HUGHES, OF BANGOR, PENNSYLVANIA.

LADDER-RAISER.

1,217,868.

Specification of Letters Patent. Patented Feb. 27, 1917.

Application filed November 17, 1916. Serial No. 131,915.

To all whom it may concern:

Be it known that I, OWEN R. HUGHES, a citizen of the United States, residing at Bangor, in the county of Northampton and State of Pennsylvania, have invented certain new and useful Improvements in Ladder-Raisers, of which the following is a specification:

This invention relates to ladder raisers, and more particularly to means for securing a ladder to a rope or cable for raising the same.

One of the main objects of the invention is to provide a device of the character stated of simple construction and operation which, when not in use, may be folded so as to occupy a minimum of space. A further object is to provide a device having adjustable securing means which may be adjusted 20 to receive the rungs of ladders of different types spaced different distances apart. Further objects will appear from the detail description.

In the drawings:—

Figure 1 is a side view of a ladder-raising device constructed in accordance with my invention,

Fig. 2 is a front view of the same,

Fig. 3 is a front view of a modified form 30 of the device, and

Fig. 4 is a side view of the same.

A central supporting strip or member 1 is provided with an aperture at its upper end which receives hook 2 secured to a rope 3 passed over a pulley 4 mounted in a block 5. The block 5 is provided with an eye 6 which receives a double hook 7 the upper end of which is passed through an eye bolt 8 secured in a beam 9 which may be secured 40 in the cable 10, of a house, barn or other building. By means of the rope 3, the free end of which may be secured in any suitable manner, the member 1 and the ladder secured thereto, in a manner to be later described, may be adjusted as described.

Two links 11 and 12 have their inner ends pivotally secured to member 1 intermediate the ends thereof by a pivot bolt 13, these two links being mounted in overlapping or 50 superposed relation. The pivot bolt 13 is also passed through the lower end of a member 14 the upper end of which is secured in spaced relation to supporting member 1 by a spacing collar 15 and a bolt 16 passed through the member 14 and collar and member 1. A lower pair of links 17 and 18 are

similarly secured to the supporting member 1 at their inner ends adjacent the lower end thereof. The outer end of link 11 is pivotally secured to the upper end of a supporting arm 19 by means of a pivot bolt 20 passed through the same and arm 19, this bolt 20 being also passed through a bracing bar 21 similar to member 14 the lower end of which is secured in spaced relation to arm 19 by means of a spacing collar 22 and a securing bolt 23 passed through the same and arm 19, the head or outer end of this bolt being countersunk into the arm 19. The outer end of link 17 is similarly secured 60 to arm 19 by means of a bolt 24 the inner end of which is also countersunk in arm 19, bracing or reinforcing elements 25 being secured above the outer end of link 17 and in spaced relation to arm 19 by a spacing collar 26 interposed between the same and member 25. The outer ends of links 12 and 18 are similarly secured to the supporting arm 19^a which is parallel with, and spaced 65 from, arm 19.

Adjacent the upper end of each arm 19 and 19^a is slidably mounted a securing clip 27 the upper end of which is arched outward to provide a receiving hook 28 for a ladder rung. The shank of each clip 27 is provided with a central longitudinally extending slot 29 through which is passed an 70 adjusting screw 30. This screw is also passed through an aperture through arm 19 or 19^a, and a wing nut 31 is threaded on to the screw in front of the clip 27. By means 75 of the wing nut the clip may be secured in any desired longitudinal adjustment on the supporting arm. The lower end portion of each arm 19 and 19^a is turned outward and 80 upward to provide an integral hook 32 adapted to receive a ladder rung. A downwardly directed securing clip 33 is mounted 85 on each supporting arm adjacent the lower end thereof and is secured in adjustment by 90 means of the screw 34 and wing nut 35. By 95 this means the distance apart of the securing clips on the supporting arms may be adjusted so as to accommodate ladders of different types in which the rungs are spaced 100 differently. By means of the clips the adjacent rungs of a ladder may be firmly secured to the supporting arms, as indicated in Fig. 2 of the drawings, so that by raising 105 the supporting member 1 as above described 110 the ladder may be secured in any desired vertical adjustment.

When the securing device is not in use the supporting arms 19 and 19^a will move downward and inward toward each other so as to be in alignment with the central 5 supporting member 1 and closely adjacent the lower end thereof, forming in this position an approximately rectangular bundle which will occupy but very little space. This folding of the securing device is per- 10 mitted by the superposed or overlapping mounting of the links. Also, by providing two pairs of links, the supporting arms are secured against free movement about their pivotal axes so as to be at all times sup- 15 ported in substantially a vertical position. When the device is in use, the clips 27 and 33, and the hooks 32, being in engagement with the adjacent rungs of the ladder, effect- 20 ually prevent movement of the supporting arms 19 and 19^a toward each other, thus holding the device in extended or operative position.

In the modified form of securing device shown in Figs. 3 and 4, the central supporting member is replaced by an approximate V-shaped supporting member 36. The ends of the arms of this member are pivotally secured to the upper ends of the supporting arms 37 by links 38. The lower end portion 30 of each arm 37 is turned outward and

upward to provide a hook 39 which coöperates with an adjustable clip 40 to receive the rung of a ladder thus firmly securing the device to the same. The supporting arms 37 and main supporting member 36 35 are thus flexibly connected so as to enable the arms to adjust themselves to the particular ladder in connection with which the device is used, thus insuring a proper and accurate hang of the ladder. 40

What I claim is:

In a device of the character described, the combination of a central supporting member, an upper pair of superposed links pivotally secured thereto at their inner ends, 45 a lower pair of superposed and similar links pivotally secured at their inner ends to said supporting member below the first of said links, supporting arms pivotally secured to the outer ends of said links and having their 50 lower ends bent to form hooks adapted to receive a ladder rung, and oppositely directed clips mounted on said arms and adjustable longitudinally of the same.

In testimony whereof I affix my signature in presence of two witnesses.

OWEN R. HUGHES.

Witnesses:

GEO. H. LEH,
ROBERT R. HUGHES.
